[57] CLAIM

The ornamental design for an inflatable retractable solar shade, as shown and described.

DESCRIPTION

FIG. 1 is a perspective view of an inflatable retractable solar shade showing my new design, the rear of the inflatable retractable solar shade being plane and unadorned.

FIG. 2 is a top plan view thereof.

FIG. 3 is a left end elevational view thereof.

FIG. 4 is a right end elevational view thereof.

FIG. 5 is a front elevational view thereof.

FIG. 6 is a rear perspective view thereof with the shade material shown fully retracted; and,

FIG. 7 is a front elevational view thereof similar to FIG. 5 with a separate cover shade material shown fully drawn.
